UNITED STATES PATENT OFFICE.

WASHINGTON H. KILBOURN, OF GREENFIELD, MASSACHUSETTS, ASSIGNOR
TO HERBERT O. EDGERTON, OF SAME PLACE.

MAGNETO-ELECTRIC STOP MECHANISM.

SPECIFICATION forming part of Letters Patent No. 443,646, dated December 30, 1890.

Application filed June 4, 1890. Serial No. 354,234. (No model.)

To all whom it may concern:

Be it known that I, WASHINGTON H. KILBOURN, a citizen of Greenfield, in the county of Franklin and State of Massachusetts, have 5 invented certain new and useful Improvements in Stop Mechanism; and I do hereby declare the following to be a full, clear, and exact description of the invention, such as will enable others skilled in the art to which 10 it appertains to make and use the same.

My invention relates to an improvement in electric stop mechanism, and is designed more particularly to be used in factories, machine-shops, mills, and like places to stop 15 the supply of power to such machinery, the object of the invention being to produce an apparatus by means of which the supply of power to machinery may be instantaneously stopped from any point in the building in 20 which the machinery is located.

A further object is to provide an apparatus by which the supply of power may be cut off from an engine or water-wheel with electrical devices, whereby the supply of power may be 25 cut off, said electrical device being capable of manipulation from any part of the building containing the machinery.

A further object is to produce an improved belt-tightener to be actuated through the 30 medium of electrical appliances.

With these objects in view the invention consists in certain novel features of construction and combinations and arrangements of parts, as hereinafter set forth, and pointed 35 out in the claims.

In the accompanying drawing the figure is a view of my invention in elevation.

The apparatus is designed to be located in proximity to the supply of power to a water- 40 wheel or steam-engine.

Mounted in suitable bearings at points near the supply of power are two pulleys A B, connected by a normally-loose belt C, the shaft of one of said pulleys (preferably pulley B) 45 being connected with the valve which controls the supply of power, whether the power or motive force be steam, water, or any other source of power. Located in proximity to the belt C is an upright D, on which a lever E is 50 pivotally supported. At the end of the short

arm of this lever a roller F is mounted and adapted to bear against the belt C, and through the medium of a weight F' on the long arm of said lever to tighten said belt when the lever E is operated, as presently explained. 55

Pivottally connected to the long arm of the lever E, and supported by a suitable bracket G', secured to the lever E, is an upwardly-projecting bar G, provided at or near its upper end with a hook or projection a. The bar G is adapted to normally engage a detent b on a shaft or arbor c, which latter is mounted in suitable supports d. A spring e is coiled about the shaft c, one end being secured to 65 said shaft and the other end to one of the supports d, whereby the detent may be returned to its normal position after the bar G shall have been released. 60

Located on a base-plate 1, having an upright 70 2, is an electro-magnet 3, and pivotally supported between the uprights 2 is an armature 4, adapted to be actuated by the magnet 3. Secured at one end to the armature 4 is a lever 5, the other end of which is pivotally connected to a horizontal bar 6, said bar passing between two rollers 7 7, between which it is adapted to have a sliding movement, being limited by a collar 8. The free end of the bar 6 is pivotally connected to a lug 9 on the 75 shaft c. 80

A foot-lever 11 is secured to the lever E, by means of which to move said lever and parts carried thereby back to their normal positions when desired. 85

A battery I is included in circuit with the coils of the magnet 3, said circuit extending to any part of the mill, factory, or other place where machinery is employed, and one or more push-buttons or circuit-closers 10 in- 90 cluded in said circuit.

When it is desired to stop the machinery in case of accident or for other reasons, one of the push-buttons will be pressed to close the circuit through the coils of magnet 3, whereby the armature 4 will be attracted and the lever 5 and bar 6 withdrawn, thus moving the detent b out of the path of the hook a of bar G, whereupon said bar will drop, and through the medium of the weight F' the roller F will be made to 100

bear on the band C and tighten it. This will cause the pulleys A B to rotate and the source of power to be shut off. After bar G has left the detent a said detent will be returned to its normal position by the springs. When it is desired to again start the mechanism, it is simply necessary to operate the foot-lever, whereupon the belt C will be loosened and the bar G moved up and made to engage the detent a, when the apparatus will be again in position to be operated to stop the mechanism.

Having fully described my invention, what I claim as new, and desire to secure by Letters Patent, is—

1. The combination, with a source of power, of a pulley connected thereto, a driving-pulley, a belt passing over said pulleys, a belt-tightener, trip mechanism, an electro-magnetic device for actuating said trip mechanism, and an electric circuit including the electro-magnetic device and circuit-closers, substantially as set forth.

2. The combination, with a source of power, of a pulley connected thereto, a driving-pulley, a belt passing over said pulleys, a pivoted lever carrying a roller to bear on said belt, a bar attached to said lever, a detent to maintain said bar normally elevated, and an electrically-actuated apparatus for manipulating said detent to release said bar, substantially as set forth.

3. The combination, with a source of power, of a pulley connected thereto, a driving-pulley, a belt passing over said pulleys, a pivoted lever carrying a roller to bear on said belt, a bar attached to said lever, a weight also attached to the lever, a pivoted detent adapted to be engaged by said bar, an electro-magnet, a lever attached to the armature of said magnet, and a rod connecting said lever with the detent, substantially as set forth.

4. The combination, with a source of power, of a pulley connected thereto, a driving-pulley, a belt passing over said pulleys, a pivoted lever carrying a roller to bear on said belt, a bar attached to said lever, a weight also attached to the lever, a pivoted detent adapted to be engaged by said bar, an electro-magnet, a lever attached to the armature of said magnet, a rod connecting said lever with the detent, and rollers for supporting said rod, substantially as set forth.

5. A stop mechanism consisting of a pulley

connected to a source of power, a loose belt 55 passing over said pulley and a driving-pulley, a pivoted lever carrying a roller to bear on said belt, a weight also attached to the lever, a pivoted detent, an electro-magnet, a lever attached to the armature of said electro-magnet, a rod connecting said lever with the detent, rollers for supporting said rod, and a stop for limiting the movement of said rod, substantially as set forth.

6. A stop mechanism consisting of a pulley 65 connected to a source of power, a loose belt passing over said pulley and a driving-pulley, a pivoted lever carrying a roller to bear on said belt, a bar attached to said lever, a weight also attached to the lever, a pivoted detent, a 70 spring for maintaining said detent normally in the path of the bar, an electro-magnet, a lever attached to the armature of said magnet, and a rod connecting said lever with the detent, substantially as set forth.

7. A stop mechanism adapted to be connected to a source of power, consisting of a pulley connected with a source of power, a driving-pulley, a loose belt passing over said pulleys, a pivoted lever, a roller mounted in 80 one end of said lever and adapted to be brought into contact with the belt, a foot-lever projecting from said pivoted lever at one end thereof, a weight attached to the other end of the lever, an upright bar having a hook-shaped upper end pivotally connected to the lever, a pivoted bar or arbor having a detent thereon with which said upright bar engages, and an electro-magnetic device for withdrawing said detent, substantially as set forth.

8. A stop mechanism consisting of a pulley connected with a source of power, a loose belt passing over said pulley and driving-pulley, a weighted lever carrying a roller adapted to bear on said belt, a bar extending upwardly 95 from said lever, a shaft carrying a detent to engage said bar, a spring on said shaft to maintain the detent in its normal position, an electro-magnet, and a rod pivotally connecting the shaft with the armature of the electro-magnet, substantially as set forth.

In testimony whereof I have signed this specification in the presence of two subscribing witnesses.
